UNITED STATES PATENT OFFICE.

BUFORD J. STEEN, OF GOOSE CREEK, TEXAS.

PIPE-GRIPPING DEVICE.

1,391,804.

Specification of Letters Patent. Patented Sept. 27, 1921.

Application filed March 5, 1919. Serial No. 280,694. Renewed July 26, 1921. Serial No. 487,722.

To all whom it may concern:

Be it known that BUFORD J. STEEN, a citizen of the United States, residing at Goose Creek, in the county of Harris and State of Texas, has invented certain new and useful Improvements in a Pipe-Gripping Device, of which the following is a specification.

This invention relates to new and useful improvements in a pipe gripping device.

One object of the invention is to provide a device of the character described, particularly adapted for use in connection with well drilling operations, and has been designed for the purpose of holding the string of pipe elevated in the bore.

In well drilling operations, as now commonly carried on, a string of pipe is let down into the bore, to the lower end of which its drill bit is attached. This string is made up of joints of pipe connected together by means of collars, and in withdrawing the pipe, it is necessary to unscrew or break the string into sections capable of being readily handled. As the string of pipe is lifted, it is necessary to hold the same sustained in the bore, so that the upper joints may be unscrewed, and when they are unscrewed and removed, the string of pipe is again elevated, and the process continues until the entire string has been withdrawn from the bore and unjointed. It is the object of this invention to hold the string in elevated position while thus being broken up or unscrewed, and separated into sections.

Another object of the invention is to provide a device of the character described, adapted to be used in letting a string down into the bore, whereby the lower portion of the string may be held sustained while additional sections are screwed to the upper end thereof.

With the above and other objects in view, the invention has particular relation to certain novel features of construction, operation and arrangements of parts, an example of which is given in this specification and illustrated in the accompanying drawings, 50 wherein:

Figure 1, is a plan view of the device, and

Fig. 2, is a side elevation thereof, shown partially in section.

Figs. 3 and 4 are plan and side view, respectively, of a modified form thereof.

Referring now more particularly to the drawings wherein like numerals of reference designate similar parts in each of the figures, the numerals, 1, 1, refer to semi-cylindrical sections, which are adapted to be fitted together, forming a cylindrical block, as shown in Fig. 1, having the central opening 2, provided to permit the string of pipe to pass through. The sections 1, 1, are secured together by means of the staples 3 and 4, which are arranged on opposite sides of the central opening 2. These staples are of an inverted U-shaped form, and their arms extend down through the respective holes 5, 5, and 6, 6, of the respective sections 1, 1, so as to hold them firmly together when in use. The sections 1, 1, are provided with the respective vertically extending slots 7, 7, wherein the radially operating dogs 8, 8, work. These dogs are elongated, their lower ends operating in the bearings 9, 9, into which the lower ends of the respective slots 7 are formed, and their upper ends are articulated and formed with ratchet teeth 10, provided to grip and hold the pipe 11. The numerals 12, 12, refer to oppositely disposed arms whose lower ends are pivoted to the respective lugs 13, 13, formed integrally with the section 1, 1. The upper ends of these arms are turned inwardly, and work through the notches 14, 14, and their inwardly turned ends are pivoted to the upper ends of the respective dogs 8, 8. Interposed between said arms and the corresponding sections 1, and secured to the latter, are the U-shaped springs 15, 15, which normally operate to hold the dogs 8 out of engagement with the pipe.

One of the U-shaped members 4, has an extension 16, forming a bearing, to the outer end of which the arcuate arms 17, 17, are pivoted, and formed integral with said arms, is the operating lever 18.

The operation of the device as follows: The sections 1, 1, are assembled on the casting head 19, on opposite sides of the pipe to be pulled and are secured together by means of the staples 4, 4. The dogs 8, 8, will thus work on opposite sides of the pipe, being normally held out of engagement with the pipe by the springs 15, 15, as explained. When the pipe is elevated, the manual lever 18 is depressed, usually by the foot of the operator, elevating the free ends of the arms 17, 17, into engagement with the arms 12, 12, 110

overcoming the pressure of the springs 15, 15, and forcing said arms and their upper ends of the dogs inwardly against the pipe. When the pipe is now released, the dog will 5 engage and hold the same elevated. They will also secure the pipe against turning in screwing the sections together or unscrewing them. When it is desired to release the dogs 8 from the pipe, the lever 18 may be 10 pulled upwardly, releasing the arms 17 from the arms 12, and permitting the springs 15, 15, to operate to release said dogs from the pipe.

In Figs. 3 and 4, a modified form of the 15 device is shown wherein the upper ends of the dogs 8, 8, are connected to the upper ends of the arms 12, 12, by means of links 12' 12', which play through the corresponding notches 14. In this form of the device, 20 the dogs 8 normally are in position to all times engage with and hold the pipe elevated. When the pipe is pulled upwardly, the dogs will automatically release it and when the pipe starts to move downwardly 25 they will engage with and hold it. When it is desired to lower the pipe into the hole, the lever 18 is depressed carrying the free ends of the arcuate arms 17, 17, up against the inner sides of the arms 12, 12, and operating through the links 12' 12', to hold the 30 dogs out of engagement with the pipe.

What I claim is:

1. A device of the character described, including a block formed of two sections and 35 having a central opening to receive a pipe, a vertical slot in each section, oppositely disposed dogs pivoted in said slots and having serrated faces, and a manually operated means for forcing said dogs into engagement with said pipe.

2. A device of the character described, including a block formed of two sections and having a central opening to receive a pipe, a vertical slot in each section, whose lower 45 end is formed into a bearing, oppositely disposed dogs working in said slots and whose lower ends rest in said respective bearings, said dogs having serrated faces, yieldable members normally holding the dogs out of engagement with the pipe and manually op-

erated means for forcing said dogs into engagement with said pipe.

3. A device of the character described, including a block having a central opening to receive a pipe, said block being formed of 55 two sections, a vertical slot in each section, said slots being oppositely arranged and their lower ends being formed with bearings, oppositely disposed, elongated dogs working in said slots and whose lower ends 60 rest in said bearings, the upper ends of said dogs being serrated to engage with said pipe, staples securing said sections together, one of said staples being formed with an extension, arcuate arms pivoted to said extension, an operating lever formed integrally with said arms, means normally holding said dogs out of engagement with said pipe, and members connected to the dogs and actuated by said arms, through 70 which said dogs may be forced into engagement with the pipe.

4. A device of the character described, including a block having a central opening to receive a pipe, opposing vertical slots cut in 75 the walls of said opening and formed at their lower ends into bearings, dogs whose lower ends work in said bearings and whose upper ends are serrated to engage with said pipe, arms pivoted to opposite sides of 80 said block, whose upper ends are inwardly turned and pivoted to the respective dogs, arcuate members pivoted at one side of the block and embracing said arms, a manual lever formed integrally with said arcuate 85 member, through which the latter is actuated into contact with said arms, whereby the dogs are forced into contact with the pipe, and yieldable members interposed between said block and arms and operating 90 to normally hold the dogs out of contact with the pipe.

In testimony whereof he has signed his name to this specification in the presence of two subscribing witnesses.

BUFORD J. STEEN.
